US0D1056618S

(12) **United States Design Patent** (10) **Patent No.:** **US D1,056,618 S**
(45) **Date of Patent:** **** Jan. 7, 2025**

(54) **BEVERAGE CONTAINER COVER**

(71) Applicant: **Xing Wang Huang**, Chang Le (CN)

(72) Inventor: **Xing Wang Huang**, Chang Le (CN)

(**) Term: **15 Years**

(21) Appl. No.: **29/872,616**

(22) Filed: **Mar. 15, 2023**

(51) **LOC (15) Cl.** **07-01**

(52) **U.S. Cl.**

USPC **D7/396.2**
